MANIFOLDING MACHINE

Frank Ronald Ford, Sparkbrook, Birmingham, England, assignor to Frank R. Ford Limited, Birmingham, England

Application September 5, 1939, Serial No. 293,518
In Great Britain August 2, 1938

8 Claims. (Cl. 101—132.5)

This invention relates to manifolding machines of the type in which a master sheet bearing in reversed script the matter to be reproduced is secured to a cylinder, the copy sheets being passed over a moistened pad against which they are pressed by a damping member and then taken between the cylinder and a pressure roller which brings them into pressure contact with the sheet.

In machines of the type aforesaid it is usual to support the bearings of the pressure roller so that they are movable towards or away from the cylinder axis, and adjustable spring means acting upon these bearings are commonly provided in order that the pressure between the roller and the cylinder may be varied as desired.

In one such arrangement, described in my prior Letters Patent No. 2,048,543, each bearing is provided with a downwardly extending rod, and a compression spring is interposed between an abutment on this rod and an angularly adjustable arm by means of which the force exerted by said spring, and tending to press the roller against the cylinder, may be controlled.

Means are provided in this type of machine for raising the damping roller or bar, at each revolution of the cylinder to allow the insertion of a fresh copy sheet, and hitherto this has been effected by mounting the damping roller or bar upon a pair of levers controlled by light springs which tend to move the roller or bar into contact with the moistened pad, said levers being engaged periodically by means of cams rotating with the cylinder.

It has been found, with existing machines, that the matter on the master sheets tends to become faint after many copies have been taken, and it is the usual practice in such circumstances to increase the pressure on the pressure roller.

Hitherto, however, this increase of pressure has not been accompanied by any increase in the amount of moisture applied to the copy sheets, and it is the object of the present invention to provide for such increased moistening.

Referring to the drawings—

Figures 1 and 2 are a side elevation and plan view, respectively, of a manifolding machine arranged in accordance with the present invention, Figure 1 being sectioned on the line 1—1 of Figure 2, and Figure 3 is a section on the line 3—3 of Figure 2.

In the construction illustrated, the apparatus comprises spaced side members 5 secured together by tie-rods 6 and having mounted between them a transversely disposed impression cylinder 7 which is provided with a clamping device 8 for

engagement with the leading edge of a master sheet (not shown) bearing in reversed script the matter to be reproduced. The clamping device may be constructed as described in my prior Letters Patent No. 2,048,543, and the spindle 9 associated with the cylinder 7 may be rotated through spur gears 10, 11, 12 from a hand crank 13.

Between the side members 5 is also arranged a tank 14 holding a moistening fluid, which is fed by suitable means to an absorbent pad 15 in a carrier 16. This container extends from one end of the tank 14 towards the cylinder 7, being disposed substantially tangentially in relation to the latter and terminating adjacent the surface 15 thereof. This part of the apparatus may be constructed in accordance with my prior Letters Patent aforesaid.

Above the moistened pad 15 is arranged a damping member extending transversely of the machine and carried by a pair of levers 17 which are pivoted on pins 18 secured to the side members 5.

The damping member aforesaid may be constructed as a bar which is fixed to the ends of the levers 17, but preferably takes the form of a roller 19, as shown.

Normally the damping member 19 rests in contact with the moistened pad 15, but is raised or moved away therefrom once in each revolution of the cylinder 7 by means of cams 20 secured to the ends of the latter.

The cams 20 may act upon rollers 21 carried by members 22 which extend downwardly from the levers 17, and these members 22 may be arranged for adjustment as described in my prior Letters Patent aforesaid.

Each time the damping member 19 is raised by the cams 20, a copy sheet (indicated at 23) may be fed beneath it to the nip between the cylinder 7 and a pressure roller 24 mounted above the latter.

The ends of the spindle 25 of this pressure roller 24 are supported in bearings 26 which are slidably in channels 27 in the side members 5 so that they can be moved towards or away from the cylinder axis.

Each of the bearings 26 is connected by a downwardly extending rod 28 to a crank arm 29 on a rock shaft 30 disposed transversely of the machine.

The connection between each crank arm 29 and the adjacent rod 28, as illustrated, is arranged in accordance with my prior Letters Patent aforesaid, it being sufficient here to say that

the screw-threaded lower end 31 of the rod 28 passes diametrically through a rotatable crank pin 32 carried by the arm 29, and that a compression spring 33 is interposed between this 5 crank pin 32 and a nut 34 on the rod.

An operating lever 35 is secured to one end of the shaft 30 externally of the adjacent side member 5, and beneath this lever 35 a rocking lever is pivoted at 36. The springs 33 tend to 10 press the lever 35 against the upper arm 37 of this rocking lever, and may be associated in this by a tension spring 38 acting on an arm 39 carried by the shaft 30.

The angular position of the lever 35, and hence 15 the pressure exerted on the cylinder by the roller 24, may be varied by oscillating the rocking lever by means of a handle 40 on the lower arm 41 thereof. This arm 41 may be provided with a spring-controlled detent 42 which co-operates 20 with recesses 43 in the side member 5 for the purpose of retaining the rocking lever in its adjusted position.

Individual adjustment of the pressures at the 25 two ends of the roller 24 may be effected by screwing the nuts 34 along the threaded parts 31 of the rods 28.

Instead of the damping member 19 being 30 pressed against the moistened pad 15 by means of torsion springs acting on the levers 17, as described in my prior Letters Patent aforesaid, there is provided above each such lever a stem 44 adapted to exert downward pressure thereon.

Each stem 44 is disposed vertically and the 35 upper part 45 thereof engages slidably with a sleeve 46 which is screw-threaded externally to engage a tapped hole in a plate 47 which is movable with the adjacent bearing 26 of the pressure roller 24.

Preferably the plate 47 is attached to a block 40 48 which is adjustably secured to the top of the bearing 26, or alternatively, the plate 47 may be carried by the associated rod 28.

A milled head 49 on the screwed sleeve 46 facilitates rotation of the latter for the purpose 45 of varying the pressure on a coiled spring 50 which is interposed between the lower end of the sleeve 46 and a shoulder 51 on the stem 44.

The lower part of the stem 44, which may be 50 of flat section, is pointed at its extremity for engagement in a conical recess 52 in the top of the lever 17, and may be slotted as at 53 to accommodate a tie-rod 54 connecting the blocks 48.

It will be seen that the arrangement above 55 described ensures that any increase which may be made in the pressure exerted on the bearings 26 by the springs 33 is automatically transmitted to the levers 17 carrying the damping member 19, and thus an increase in the amount of moisture applied to the copy sheets is obtained whenever the pressure on the roller 24 is increased. Furthermore, the provision of the rotatable sleeves 46 and springs 50 allows individual adjustment of the pressures acting on the two levers 17.

It is found that the noise produced in existing 65 machines by the upward and downward movements of the damping member 19, and the latter's tendency to bounce after dropping on to the copy sheet 23, is greatly reduced or eliminated by the use of the arrangement above described.

70 What I claim then is:

1. A manifolding machine comprising a stationary frame, a rotatable cylinder having means for attaching a master sheet thereto, a roller co-operating with said cylinder and adapted to bring 75 a copy sheet into pressure contact with the master sheet thereon, a stationary moistened pad

for damping said copy sheet before contact with said master sheet, a damping member adapted to press said copy sheet against said pad, pivoted levers carrying said damping member, means for adjusting said roller towards the axis of said cylinder to increase its pressure on the latter, and mechanical means acting upon said levers to effect in response to such adjustment an automatic increase in the pressure exerted by said damping member on said pad and hence in the amount of moisture transmitted therefrom to said copy sheet. 5

2. A manifolding machine comprising a stationary frame, a rotatable cylinder having means for attaching a master sheet thereto, a roller co-operating with said cylinder and adapted to bring a copy sheet into pressure contact with the master sheet thereon, bearings supporting the ends of said roller and slidably adjustable on said frame towards the axis of said cylinder to increase the 20 pressure exerted on the latter by said roller, a stationary moistened pad for damping said copy sheet before contact with said master sheet, a damping member adapted to press said copy sheet against said pad, pivoted levers carrying said 25 damping member, and means mechanically coupling said bearings to said levers for effecting an automatic increase in the pressure exerted by said damping member on said pad and hence in the amount of moisture transmitted therefrom to 30 said copy sheet in response to adjustment of said roller towards the axis of said cylinder.

3. A manifolding machine comprising a stationary frame, a rotatable cylinder having means for attaching a master sheet thereto, a roller co-operating with said cylinder and adapted to bring a copy sheet into pressure contact with the master sheet thereon, bearings supporting the ends of said roller and slidably adjustable on said frame towards the axis of said cylinder to increase the 40 pressure exerted by the latter on said roller, a stationary moistened pad for damping said copy sheet before contact with said master sheet, a damping member adapted to press said copy sheet against said pad, pivoted levers carrying said damping member, and stems carried by said bearings and adapted to exert a pressure upon said levers which increases as said roller is adjusted towards the axis of said cylinder, such adjustment thus being automatically accompanied by 45 an increase of the pressure exerted by said damping member on said pad and hence in the amount of moisture transmitted therefrom to said copy sheet. 50

4. A manifolding machine comprising a stationary frame, a rotatable cylinder having means for attaching a master sheet thereto, a roller co-operating with said cylinder and adapted to bring a copy sheet into pressure contact with the master sheet thereon, bearings supporting 60 the ends of said roller and mounted on said frame for sliding movement towards and away from said cylinder, a stationary moistened pad for damping said copy sheet before contact with said master sheet, a damping member adapted to press said copy sheet against said pad, pivoted levers carrying said damping member and blocks mounted on said bearings, stems carried by said blocks and adapted to press downwards upon the tops of said levers, whereby an increase in the pressure between said roller and said cylinder is automatically accompanied by an increase of the pressure exerted by said damping member on said pad and hence in the amount of moisture 65 transmitted therefrom to said copy sheet. 70

75

5. A manifolding machine comprising a stationary frame, a rotatable cylinder having means for attaching a master sheet thereto, a roller co-operating with said cylinder and adapted to bring a copy sheet into pressure contact with the master sheet thereon, bearings supporting the ends of said roller and mounted on said frame for sliding movement towards and away from said cylinder, a stationary moistened pad for damping said copy sheet before contact with said master sheet, a damping member adapted to press said copy sheet against said pad, pivoted levers carrying said damping member, a bracket carried by each of said bearings, an adjustable screwed sleeve engaging a tapped hole in said bracket, and a stem slidably mounted in said sleeve and pressed by the latter towards the adjacent lever, whereby an increase in the pressure between said roller and said cylinder is automatically accompanied by an increase in the pressure exerted by said damping member on said pad, and pressure exerted by the two ends of said damping member being variable individually by adjustment of said sleeves.
10. 6. A manifolding machine comprising a stationary frame, a rotatable cylinder having means for attaching a master sheet thereto, a roller co-operating with said cylinder and adapted to bring a copy sheet into pressure contact with the master sheet thereon, bearings supporting the ends of said roller and mounted on said frame for sliding movement towards and away from said cylinder, a stationary moistened pad for damping said copy sheet before contact with said master sheet, a damping member adapted to press said copy sheet against said pad, pivoted levers carrying said damping member, a bracket carried by each of said bearings, an adjustable screwed sleeve engaging a tapped hole in said bracket, and a shouldered stem slidably mounted in said sleeve, and a spring acting between the shoulder on said sleeve and the end of said stem and pressing the latter towards the adjacent lever, whereby an increase in the pressure between said roller and said cylinder is automatically accompanied by an increase in the pressure exerted by said damping member on said pad, the pressure exerted by the two ends of said damping member
- being variable individually by adjustment of said sleeves.
7. A manifolding machine comprising a stationary frame a rotatable cylinder having means for attaching a master sheet thereto, a roller co-operating with said cylinder and adapted to bring a copy sheet into pressure contact with the master sheet thereon, bearings supporting the ends of said roller and mounted on said frame for sliding movement towards and away from said cylinder, a stationary moistened pad for damping said copy sheet before contact with said master sheet, a damping member adapted to press said copy sheet against said pad, pivoted levers carrying said damping member, and stems carried by said bearings and adapted to exert a downward pressure upon said levers, said stems being pointed at their ends for engagement with conical recesses in said levers, whereby an increase in the pressure between said roller and said cylinder is automatically accompanied by an increase of the pressure exerted by said damping member on said pad and hence in the amount of moisture transmitted therefrom to said copy sheet.
25. 8. A manifolding machine comprising a stationary frame, a rotatable cylinder having means for attaching a master sheet thereto, a roller co-operating with said cylinder and adapted to bring a copy sheet into pressure contact with the master sheet thereon, bearings supporting the ends of said roller and mounted on said frame for sliding movement towards and away from said cylinder, a stationary moistened pad for damping said copy sheet before contact with said master sheet, a damping member adapted to press said copy sheet against said pad, pivoted levers carrying said damping member, blocks mounted on said bearings, a tie-rod connecting said blocks, and stems slidably supported upon said blocks and slotted to clear said tie-rod, said stems being adapted to press downwards upon the tops of said levers, whereby an increase in the pressure between said roller and said cylinder is automatically accompanied by an increase of the pressure exerted by said damping member on said pad and hence in the amount of moisture transmitted therefrom to said copy sheet.

FRANK RONALD FORD.
